UNITED STATES PATENT OFFICE

LOUIS A. MAXSON, OF CLAREMONT, NEW HAMPSHIRE, ASSIGNOR TO SULLIVAN MACHINERY COMPANY, A CORPORATION OF MASSACHUSETTS

MINING MACHINE

Application filed June 20, 1927. Serial No. 200,096.

This invention pertains to mining machines and more particularly, but not exclusively, to an improved feeding mechanism for a coal mining machine of the longwall type.

An object of this invention is to provide an improved mining machine feeding mechanism which is of an exceedingly simple, rugged, and compact character. Still another object of this invention is to provide an improved mining machine having a pressure fluid actuated driving motor of the intermeshing rotor type and improved and simplified feeding mechanism driven by said motor. A further object is to provide an improved mining machine feeding mechanism wherein the feed gearing is greatly simplified and the number of parts reduced to a minimum, thereby rendering the machine exceedingly compact. Another object is to provide an improved mining machine feeding mechanism of the planetary gear type associated with the intermeshing motor rotors of the fluid actuated driving motor whereby the opposite rotation of the rotors is taken advantage of to obtain a substantial speed reduction. Still another object of this invention is to provide a coal mining machine having a fluid actuated driving motor of the intermeshing rotor type and an improved feeding mechanism driven thereby including planetary gearing whereby the machine is fed at different speeds, one feeding speed being effected when the planetary gearing is connected to one rotor and a different speed effected when both rotors are utilized in driving the planetary gearing. These and other objects and advantages of the invention will subsequently appear.

In the accompanying drawings I have shown for purposes of illustration one form 40 which the invention may assume in practice.

In these drawings,—

Fig. 1 is a plan view of the improved mining machine showing the cutter bar in a plurality of operative positions, parts being 45 shown in section to illustrate details of construction.

Fig. 2 is a longitudinally extending vertical sectional view taken substantially on line 2—2 of Fig. 1.

Fig. 3 is a fragmentary horizontal sectional

view taken substantially on line 3—3 of Fig. 2, parts being shown in plan to facilitate illustration.

Fig. 4 is a central longitudinally extending vertical sectional view taken on line 4—4 of Fig. 1.

Fig. 5 is a detail sectional view taken on line 5—5 of Fig. 3.

In accordance with this illustrative embodiment of the invention there is shown a mining machine of the flexibly fed continuous cutter longwall type having a generally rectangular machine frame 1 slideable on its bottom 2 on the mine floor. The frame 1 comprises a motor section 3, a feed section 4 and a cutter section 5, said motor section 3 being interposed between said feed and cutter sections and suitably rigidly connected thereto. The sections when connected, form a smooth bottom shoe on which the machine is slideable. As shown, pivotally mounted at 6 on a vertical axis at the rear end of the machine frame 1 is an elongated plane cutter bar 7 about the margin of which an endless cutter bit carrying cutter chain 8 is adapted to be circulated. As is usual in mining machines of the type disclosed, the cutter bar 7 is adapted to be swung or slued to either side of the frame at right angles to the longitudinal axis of the machine or to be disposed lengthwise of the machine. The cutter bar 7 is adapted to be locked in its different operative positions by means of a locking pin 9 which is adapted to be inserted in any one of a plurality of apertures 10 formed in the frame section 5 to lock the cutter bar to the frame. In accordance with this illustrative embodiment of the invention the motor section 3 has housed therein a pressure fluid actuated motor comprising intermeshing spiral toothed motor rotors 11 and 12 disposed on parallel horizontal axes extending longitudinally of the machine. A usual reversing mechanism is interposed between the rear end of the motor and the cutting mechanism and this reversing mechanism is adapted to connect the cutter chain 8 alternatively to the rotors 11 and 12 to effect movement of the cutter chain selectively in opposite directions during cutting in a well known manner.

As shown in the drawings, the improved feeding mechanism specifically comprises a spur pinion 13 rotatably mounted on a forwardly projecting portion 14 of the supporting shaft for the rotor 11. The spur pinion 13 meshes with a spur gear 15 rotatably mounted on a stub shaft 16 suitably rigidly secured within the frame section 4, the shaft 16 being disposed parallel with the rotor shafts. As illustrated, the gear 15 meshes with a larger spur gear 17 having a hub 18 rotatably mounted on a bearing sleeve 19 supported on a forwardly projecting reduced portion 20 of the supporting shaft for the rotor 12. Fixed, as at 21, to the reduced portion 20 of the rotor shaft is a spur pinion 22 which meshes with a plurality of planetary gears 23 rotatably mounted on horizontally disposed stub shafts 24 disposed parallel with the rotor shafts. The shafts 24 are herein preferably formed integral with a spider member or planet carrier 25 keyed at 26 to a horizontal shaft 27 alined with the supporting shaft for the rotor 12. The planetary gears 23 also mesh with an internal gear 28 formed within the spur gear 17. As shown in Fig. 2 the shaft 27 is journaled at its opposite ends in ball bearings 29 and 30, respectively, the latter bearing being carried by a detachable bearing bracket 31 suitably bolted to a detachable cap member 32 carried by the frame section 4. Referring more particularly to Fig. 3 it will be noted that the spur pinion 13 is held in position on the portion 14 of the supporting shaft for the rotor 11 by means of a split ring 33, while the spur gear 15 is positioned on the shaft 16 by a similar ring 34. It will also be noted that the forward end of the shaft 16 is secured by a key 35 within a supporting bracket 36, while the rear end of the shaft 16 is fixed by a key 37 to the frame section 4. Keyed for sliding movement on the reduced portion 14 on the supporting shaft of the rotor 11 and on the shaft 16 are jaw clutch members 38 and 39, respectively. The clutch member 38 has formed on the rear face thereof clutch teeth 40 which are adapted to cooperate with corresponding clutch teeth 41 formed on the forward face of the pinion 13. The clutch member 39 is provided with clutch teeth 42 which are adapted to cooperate with clutch teeth 43 formed on the gear 15. The clutch members 38 and 39 are adapted to be shifted to connect alternatively the gears 13, 15 to their respective shafts and the mechanism for shifting these clutch members comprises a double shipper yoke 44 (see Fig. 5) having inwardly projecting lugs 45 which cooperate with peripheral grooves 46 formed in the clutch members. The shipper yoke 44 is pivoted at 47 on an upstanding bracket 48 carried by the frame section 4. The outer end of the shipper yoke 44 is pivotally connected at 49 to a horizontally disposed shipper rod 50 extend-

ing longitudinally of and guided by the machine frame. The rod 50 has suitably secured thereto at its forward end a grasping handle 51. Thus it will be evident that when the operator grasps the handle 51 and slides the rod 50 rearwardly, the teeth 40 on the clutch member 38 are connected to the teeth 41 on the pinion 13 while the clutch member 39 is released from the gear 15. When the rod 50 is moved in the opposite direction, the teeth 42 on the clutch member 39 are connected to the teeth 43 on the gear 15 while the clutch member 38 is released from the pinion 13. It is therefore evident that the gears 13 and 15 are alternatively connected to their respective shafts. 70 75 80

Again referring to the specific feed gearing it will be observed that the shaft 27 has suitably fixed thereto intermediate its ends a worm 52 which meshes with a horizontally disposed worm gear 53 rotatably mounted on a vertically disposed shaft 54, the latter being located in the longitudinal center of the machine in advance of the gearing 13, 15, 17. The shaft 54 is journaled at its upper end in ball bearings 55 suitably carried by the frame section 4 and the lower end of this shaft has fixed thereto by a key 56 a spur pinion 57. The hub of the spur pinion 57 is rotatably mounted in a ball bearing 58 likewise carried by the frame section 4. As illustrated, the worm gear 53 is adapted to be frictionally connected to the shaft 54 by means of a friction disc clutch comprising a clutch housing 59 keyed at 60 to the hub of the worm gear 53. 90 95 100 The housing 59 carries a series of clutch discs 61 which are interleaved with corresponding series of clutch discs 62 carried by a clutch member 63 keyed at 64 to the shaft 54. Encircling the shaft 54 is a clutch applying member 65 having depending fingers 66 which engage the upper disc of the series of clutch discs 61, 62. Engaging the plane upper surface of the clutch member 65 are rollers 67 carried by a shipper yoke 68 pivotally mounted at 69 on the feed frame section. The shipper yoke 68 has fixed thereto an arm 70 projecting forwardly through an opening 71 in the machine frame and this arm is pivotally connected at its front end at 72 to a link 73. The link 73 is in turn pivotally connected at 74 to a member 75 suitably fixed to a horizontal rod 76 extending longitudinally of and guided by the machine frame. The outer end of the rod 76 is threadedly connected at 77 to a rotatable nut 78 mounted within a bore 79 formed in the frame section 4. The nut 78 has preferably formed integral therewith an operating handle 80. It is clearly evident that when the handle 80 is suitably manipulated the rod 76 is moved forwardly, thereby causing the link 73 to swing the arm 70 upwardly, thereby swinging the shipper yoke 68 about its pivot and depressing the clutch applying member 65. 110 115 120 125 130

to apply the clutch. As clearly shown in Fig. 4 the spur pinion 57 meshes with an internal gear 81 herein formed integral with a horizontally disposed feed operating member, herein a winding drum 82. The hub 83 of the drum 82 is rotatably mounted on ball bearings 84 supported on a vertically disposed stud 85 suitably secured to the machine frame. The hub 83 has an upper cylindrical portion 86 mounted within a depending flange 87 formed on the machine frame. Co-operating with the winding drum 82 is a usual flexible feeding element herein in the form of a feed cable 88, while disposed at the opposite forward corners of the machine frame are guide rolls 89 rotatably mounted on vertical studs 90.

The proportions between the sizes of the various gears necessary to obtain the desired ratio between the high and low speeds may be calculated by the use of any standard epicyclic gear formula found in mechanical engineering handbooks. As an illustration, it may readily be ascertained that by providing a ratio between the teeth on the pinion 13 and the gear 17 of 9 to 30 and providing a ratio between the teeth on the pinion 22 and internal gear 28 of 3 to 1, there will be obtained a fast speed ten times as fast as the cutting speed, the fast speed being obtained when the integrally connected gears 17 and 28 are held stationary and the slow or cutting speed being obtained when these gears are rotated in a direction opposite to the direction of rotation of the pinion 22. It will further be evident that by making the ratio between the teeth on the gears 13 and 17 large enough the slow speed drive could be made opposite in direction to the fast speed drive, an arrangement which would be desirable if a chain and sprocket feed instead of a cable and drum feed were to be employed.

The operation of the improved mining machine will be clearly apparent from the description given. When it is desired to move the machine rapidly about the mine, for instance during positioning of the machine relative to the working face, the feed cable 88 is extended from the winding drum 82 and is anchored at its free end to a suitable roof jack adjacent the coal face. When the machine is being moved in this manner the cutter bar 7 is swung to a position lengthwise of the machine and rigidly locked to the machine frame by the pin 9. The operator then grasps the handle 51 and slides the rod 50 forwardly thereby connecting the gear 15 to the stationary shaft 16 and releasing the pinion 13 from the supporting shaft 55 for the rotor 11. Consequently the gear 15 is held against rotation and due to its meshing engagement with the spur gear 17 the latter is also held immovable. Upon admission of pressure fluid to the motor the rotors 11, 12 revolve in opposite directions and con-

sequently the pinion 22 is rotated, thereby rotating the planetary gears 23, causing the latter to roll around the stationary internal gear 28 as a trackway, thereby effecting movement of the planet carrier 25 and shaft 27 at a relatively high speed. The operator then grasps the handle 80 and the clutch 61, 62 is applied, connecting the worm gearing to the driving pinion 57, thereby causing the feed drum 82 to wind in the feed cable 88 at a relatively fast or machine moving speed. After the machine is suitably positioned at the working face, the clutch members 38, 39 are moved to their neutral position and the clutch 61, 62 released. The feed cable 88 is then extended around the guide roll 89 nearest the face and rearwardly as indicated by dotted lines in Fig. 1 and suitably connected to the cutter bar 7. The operator then shifts the rod 50 rearwardly connecting the pinion 13 to the reduced portion 14 of the supporting shaft of the rotor 11, the gear 15 being disconnected from the shaft 16 and freely rotatable relative thereto. The gear 17 is then rotated by the gearing 13, 15 simultaneously as the gear 22 rotates and consequently as the planetary gears 23 roll around the then rotating internal gear 28 the spider 25 and shaft 27 are rotated at a relatively reduced speed. It is obvious that the internal gear 28 rotates in a direction reverse to the direction of orbital movement of the planetary gear 23 due to the reverse rotation of the motor rotors thereby substantially decreasing the speed of rotation of the planet carrier 25. The operator then applies the clutch 61, 62 connecting the feed drum 82 to the motor and consequently the feed cable 88 is wound in at a relatively slow or cutting speed and the cutter bar swung from the dotted line position shown in Fig. 1 to the full line position, the cutter bar thereafter being locked to the frame by the pin 9. The clutch 61, 62 is then released and the feed cable extended forwardly of the machine and anchored at its free end to a suitable roof jack. The clutch 61, 62 is then again applied and the feed cable wound in by the feed drum 82 and the machine moved relative to the coal face at a relatively slow cutting speed. It is obvious that when it is desired to cut at an opposite face or in the opposite direction at the same face the cutter bar may be swung to the opposite side of the machine, the cutter chain reversed and the cutter bits turned in their respective links and the feed cable reversely wound on the feed drum and extended from the opposite side of the machine. These and other uses and advantages of my improved mining machine will be clearly apparent to those skilled in this art.

While I have in this application specifically described one form which my invention may assume in practice, it will be under-

stood that this form of the same is used for purposes of illustration and that the invention may be modified and embodied in various other forms without departing from its spirit or the scope of the appended claims.

5 What I claim as new and desire to secure by Letters Patent is:

1. In a mining machine, feeding mechanism comprising a plurality of driving members disposed on parallel axes in the same transverse plane and simultaneously rotatable at equi-angular rates in opposite directions, a feed operating member adapted to cooperate directly with flexible feeding means to move the machine towards an extraneous point to which said flexible feeding means extends, and plural speed driving gearing for said feed operating member including a pair of coaxial gear elements arranged to be simultaneously driven respectively by said driving members in opposite directions at different speeds, and one drivable by its respective driving member while the other is not driven by its respective driving member.

25 2. In a mining machine, feeding mechanism including a plurality of driving members simultaneously rotatable at equi-angular rates in opposite directions, a feed operating member adapted to cooperate directly with flexible feeding means, and plural speed driving gearing between said driving members and said feed operating member including a spur gear driven only by one of said driving members, an internal gear driven only by the other of said driving members, and planetary gears connecting said spur gear and said internal gear.

3. In a mining machine, feeding mechanism including a plurality of driving members simultaneously rotatable at equi-angular rates in opposite directions, a feed operating member adapted to cooperate directly with flexible feeding means, and plural speed driving gearing between said driving members and said feed operating member including a spur gear driven only by one of said driving members, an internal gear driven only by the other of said driving members, planetary gears connecting said spur gear and said internal gear, means for disconnecting said internal gear from its driving member, and means for holding said internal gear stationary when the same is disconnected from its respective driving member.

55 4. In a mining machine, feeding mechanism including a plurality of driving members simultaneously rotatable in opposite directions, a feed operating member adapted to cooperate directly with flexible feeding means, and plural speed driving gearing between said driving members and said feed operating member including a spur gear driven only by one of said driving members, an internal gear driven only by the other of said driving members, planet gears connecting

said spur gear and said internal gear, said feed operating member being driven at one feeding speed when said spur gear and said internal gear are simultaneously driven by their respective driving members, means for disconnecting said internal gear from its driving member, and means for holding said internal gear stationary when disconnected from its driving member to effect drive of said feed operating member at a different feeding speed.

5. In a mining machine, a driving motor having rotors rotating in opposite directions, and feeding mechanism including a feed operating member adapted to cooperate directly with flexible feeding means and driving gearing for said feed operating member simultaneously operatively connected to both rotors and including a gear element driven by only one of said rotors, a gear element driven only by the other of said rotors and cooperating gear elements simultaneously driven by said gear elements at different speeds.

6. In a mining machine, a pressure fluid actuated driving motor having intermeshing rotors rotating in opposite directions, and feeding mechanism including a feed operating member adapted to cooperate directly with flexible feeding means, and driving gearing for said feed operating member simultaneously operatively connected to both rotors and including a gear element driven by only one of said rotors, a gear element driven only by the other of said rotors, and cooperating gear elements simultaneously driven by said gear elements at different speeds.

7. In a mining machine, a pressure fluid actuated driving motor having intermeshing rotors rotating in opposite directions, and feeding mechanism including a feed operating member adapted to cooperate directly with flexible feeding means, and planetary driving gearing for said feed operating member simultaneously operatively connected to both rotors and including a gear element driven by only one of said rotors, a gear element driven only by the other of said rotors, and cooperating gear elements simultaneously driven by said gear elements at different speeds.

8. In a mining machine, a pressure fluid actuated driving motor having intermeshing rotors rotating in opposite directions, and feeding mechanism driven thereby including a feed operating member adapted to cooperate directly with flexible feeding means and including driving gearing for said feed operating member, said gearing when connected to only one rotor and disconnected from the other rotor effecting rotation of said feed operating member at one feeding speed and when connected simultaneously to both rotors effecting rotation of said feed operating member at a different feeding speed, and means for effecting such connections.

9. In a mining machine, a pressure fluid actuated driving motor having intermeshing rotors rotating in opposite directions, and feeding mechanism driven thereby including a feed operating member adapted to cooperate directly with flexible feeding means, and driving gearing for said feed operating member, said gearing when connected to only one rotor and disconnected from the other rotor 5
10 effecting rotation of said feed operating member at a relatively high speed and when connected simultaneously to both rotors effecting rotation of said feed operating member at a substantially reduced speed, and means 15 for effecting such connections.
10. In a mining machine, a pressure fluid actuated driving motor having intermeshing rotors rotating in opposite directions, and feeding mechanism driven thereby including a feed operating member adapted to cooperate directly with flexible feeding means, and planetary driving gearing for said feed operating member, said planetary gearing when connected to only one rotor and disconnected 20 from the other rotor effecting rotation of said feed operating member at a relatively high speed and when connected simultaneously to both rotors effecting rotation of said feed operating member at a substantially reduced speed, and means for effecting such connections.
11. In a mining machine, a pressure fluid actuated driving motor having intermeshing rotors rotating in opposite directions, and feeding mechanism driven thereby including a feed operating member adapted to cooperate directly with flexible feeding means, and driving gearing for said feed operating member including a rotatable member, and planetary gearing associated therewith, said rotatable member when connected to only one of said rotors and said planetary gearing connected to only the other rotor effecting rotation of said feed operating member at one 25 feeding speed and when said rotatable member is disconnected from its driving rotor and held stationary effecting rotation of said feed operating member at a different feeding speed directly from said other rotor through 30 said planetary gearing, means for effecting such connections, and means for holding said rotatable member stationary.
12. In a mining machine, a pressure fluid actuated driving motor having intermeshing rotors rotating in opposite directions, and feeding mechanism driven thereby including a feed operating member adapted to cooperate directly with flexible feeding means and driving gearing for said feed operating member, said driving gearing including a spur gear driven only by one of said rotors, an internal gear driven only by the other of said rotors, and planet gears connecting said spur gear and said internal gear.
13. In a mining machine, a pressure fluid actuated driving motor having intermeshing rotors rotating in opposite directions, and feeding mechanism driven thereby including a feed operating member adapted to cooperate directly with flexible feeding means, and driving gearing for said feed operating member, said driving gearing including a spur gear driven only by one of said rotors, an internal gear driven only by the other of said rotors, planet gears connecting said spur gear and said internal gear, means for disconnecting said internal gear from its respective driving rotor, and means for holding said internal gear stationary when the same is disconnected from its respective driving rotor.
14. In a mining machine, a pressure fluid actuated driving motor having intermeshing rotors rotating in opposite directions, and feeding mechanism driven thereby including a feed operating member adapted to cooperate directly with flexible feeding means and driving gearing for said feed operating member, said driving gearing including a spur gear driven only by one of said rotors, an internal gear driven only by the other of said rotors, planet gears connecting said spur gear and said internal gear, said feed operating member being driven at one feeding speed when said spur gear and said internal gear are simultaneously driven by their respective driving rotors and driven at a different feeding speed when said internal gear is disconnected from its rotor and held stationary, means for disconnecting said internal gear from its respective rotor, and means for holding said internal gear stationary.
15. In a mining machine, feeding mechanism comprising a plurality of driving members simultaneously rotatable at equi-angular rates in opposite directions, a feed operating member adapted to cooperate directly with flexible feeding means to move the machine towards an extraneous point to which said flexible feeding means extends, and plural speed driving gearing for said feed operating member operatively connectible to both of said driving members, said gearing when connected to only one of said driving members and disconnected from the other effecting rotation of said feed operating member at one feeding speed and when connected simultaneously to both of said driving members effecting rotation of said feed operating member at a different feeding speed, and means for effecting such connections.
16. In a mining machine, feeding mechanism comprising a plurality of driving members simultaneously rotatable at equi-angular rates in opposite directions, a feed operating member adapted to cooperate directly with flexible feeding means to move the machine towards an extraneous point to which said flexible feeding means extends, and driv-

- ing gearing between said driving members and said feed operating member, said gearing when connected to only one of said driving members and disconnected from the other 5 effecting rotation of said feed operating member at a relatively high speed and when connected simultaneously to both of said driving members effecting rotation of said feed operating member at a substantially reduced speed, and means for effecting such connections.
17. In a mining machine, feeding mechanism comprising a plurality of driving members simultaneously rotatable at equi-angular rates in opposite directions, a feed operating member adapted to cooperate directly with flexible feeding means, and planetary driving gearing between said driving members and said feed operating member, said 10 planetary gearing when connected to only one of said driving members and disconnected from the other effecting rotation of said feed operating member at a relatively high speed and when connected simultaneously to both of said driving members effecting rotation of said feed operating member at a substantially reduced speed, and means for effecting such connections.
18. In a mining machine, a pressure fluid actuated driving motor having intermeshing rotors rotating in opposite directions, and feeding mechanism driven thereby including a feed operating member adapted to cooperate directly with flexible feeding means, driving gearing between said motor and said feed operating member comprising a gear driven only by one of said rotors and a gear driven only by the other of said rotors, and planet gears connecting said gears.
19. In a mining machine, a pressure fluid actuated driving motor having intermeshing rotors rotating in opposite directions, and feeding mechanism driven thereby including a feed operating member adapted to cooperate directly with flexible feeding means, driving gearing between said motor and said feed operating member comprising a gear driven only by one of said rotors and a gear driven only by the other of said rotors, planet 40 gears connecting said gears, means for disconnecting one of said gears from its driving rotor, and means for holding said gear stationary when the same is so disconnected.
20. In a mining machine, a pressure fluid actuated driving motor having intermeshing rotors rotating in opposite directions, and feeding mechanism driven thereby including a feed operating member adapted to cooperate directly with flexible feeding means, and 45 driving connections between said motor and said feed operating member including a gear rotatable with one rotor, a gear rotatable with the other rotor, and planet gears connecting said gears, said feed operating member being driven at one feeding speed when 50 said gears are simultaneously driven by both of said rotors and driven at a different feeding speed when one of said gears is disconnected from its rotor and held stationary, means for disconnecting said latter gear from its rotor, and means for holding said latter gear stationary.
21. In a mining machine, a motor comprising a pair of intermeshing toothed rotors rotating at equi-angular rates in opposite directions, a feed operating member adapted to cooperate directly with flexible feeding means, and plural speed driving connections between said motor and said feed operating member including a gear connected to each of 55 said rotors and adapted to be simultaneously driven thereby, and planet gears meshing with said gears.
22. In a mining machine, feeding means including a plurality of driving members simultaneously rotatable at equi-angular rates in opposite directions, a feed operating member adapted to cooperate directly with flexible feeding means and plural speed driving gearing for said feed operating member including gear elements simultaneously driven directly by said driving members, a gear element driven by one of said gear elements, and orbitally movable gearing connecting the other of said first mentioned gear elements and said second mentioned gear element in driving relation.
23. In a mining machine, feeding mechanism including a plurality of driving members simultaneously rotatable at equi-angular rates in opposite directions, a feed operating member adapted to cooperate directly with flexible feeding means, and plural speed driving gearing for said feed operating member including gear elements driven directly by said driving members, an internal gear driven by one gear element, and planet gears meshing with said other gear element and said internal gear.
24. In a mining machine, a machine frame adapted to rest upon and slide in any direction over the mine bottom, a motor carried by said frame, cutting mechanism including a kerf cutter projecting from said frame, and flexible feeding means for the machine including a rotatable feed member and a co-operating flexible feeding element, and plural speed driving connections between said motor and said feed member including a plurality of concentrically arranged driving gears, the inner gear being continuously driven, a driven member operatively connected to said feed member, planet gears operatively connected to said driven member and meshing with said drive gears, and mechanism for effecting rotation of said drive gears simultaneously or one independently of the other.
25. In a mining machine, a machine frame adapted to rest upon and slide in any

direction over the mine bottom, a motor carried by said frame, cutting mechanism including a kerf cutter projecting from said frame, and flexible feeding means for the machine including a rotatable feed member and a cooperating flexible feeding element, and plural speed driving connections between said motor and said feed member including a plurality of concentrically arranged driving gears, the inner gear being continuously driven, a driven member operatively connected to said feed member, planet gears meshing with said drive gears, and mechanism for effecting simultaneous rotation of said drive gears in opposite directions.

26. In a mining machine, a machine frame adapted to rest upon and slide in any direction over the mine bottom, a motor carried by said frame, cutting mechanism including a kerf cutter projecting from said frame, and flexible feeding means for the machine including a rotatable feed member and a cooperating flexible feeding element, and plural speed driving connections between said motor and said feed member including a plurality of concentrically arranged driving gears, the inner gear being continuously driven, a driven member operatively connected to said feed member, planet gears meshing with said drive gears, and mechanism for effecting simultaneous rotation of said drive gears in opposite directions or for holding one of said drive gears stationary while the other gear is driven.

27. In a mining machine, feeding mechanism including a plurality of driving members, a feed operating member adapted to cooperate directly with flexible feeding means and plural speed driving gearing for said feed operating member including gear elements driven directly by said driving members, one of which is continuously driven at all speeds, an internal gear driven by one gear element, and planet gears meshing with said other continuously driven gear element and said internal gear.

28. In a mining machine, feeding mechanism including a plurality of driving members, a feed operating member adapted to cooperate directly with flexible feeding means, and plural speed driving gearing between said driving members and said feed operating member including a spur gear driven only by one of said driving members and continuously driven at all speeds, an internal gear driven only by the other of said driving members, and planetary gears connecting said continuously driven spur gear and said internal gear.

29. In a mining machine, feeding mechanism including a plurality of driving members, a feed operating member adapted to cooperate directly with flexible feeding means, and plural speed driving gearing between said driving members and said feed

operating member including a spur gear driven only by one of said driving members, an internal gear driven only by the other of said driving members, planetary gears connecting said spur gear and said internal gear, means for disconnecting said internal gear from its driving member, and means for holding said internal gear stationary when the same is disconnected from its respective driving member.

30. In a mining machine, feeding mechanism including a plurality of driving members, a feed operating member adapted to cooperate directly with flexible feeding means, and plural speed driving gearing between said driving members and said feed operating member including a spur gear driven only by one of said driving members, an internal gear driven only by the other of said driving members, planet gears connecting said spur gear and said internal gear, said feed operating member being driven at one feeding speed when said spur gear and said internal gear are simultaneously driven by their respective driving members, means for disconnecting said internal gear from its driving member, and means for holding said internal gear stationary when disconnected from its driving member to effect drive of said feed operating member at a different feeding speed.

31. In a mining machine, a driving motor having a pair of motor rotors, and feeding mechanism including a feed operating member adapted to cooperate directly with flexible feeding means, and driving gearing for said feed operating member simultaneously operatively connected to both rotors and including a gear element driven by only one of said rotors, a gear element driven only by the other of said rotors and cooperating gear elements simultaneously driven by said gear elements at different speeds.

32. In a mining machine, a pair of driving members, and feeding mechanism driven thereby including a feed operating member adapted to cooperate directly with flexible feeding means, and driving gearing for said feed operating member, said driving gearing including a spur gear driven only by one of said driving members, an internal gear driven only by the other of said driving members, planet gears connecting said spur gear and said internal gear, means for disconnecting said internal gear from its respective driving member, and means for holding said internal gear stationary when the same is disconnected from its respective driving member.

33. In a mining machine, a pair of driving members, and feeding mechanism driven thereby including a feed operating member adapted to cooperate directly with flexible feeding means, and driving gearing for said feed operating member, said driving gearing including a spur gear driven by only one of

185 said driving members, an internal gear driven only by the other of said driving members, planet gears connecting said spur gear and said internal gear, said feed operating member being driven at one feeding speed when said spur gear and said internal gear are simultaneously driven by their respective driving members and driven at a different feeding speed when said internal gear is disconnected from its driving member and held stationary, means for disconnecting said internal gear from its respective driving member, and means for holding said internal gear stationary when so disconnected.

190 34. A mining machine feeding mechanism comprising a feed operating member adapted to cooperate directly with flexible feeding means, and motor operated driving means for said member including parallel shafts, 195 spur gears driven by said shafts respectively, an internal gear driven by one of said gears, planet gears meshing with said other gear and said internal gear, and driving connections between said planet gears and said feeding operating member.

200 35. A mining machine feeding mechanism comprising a feed operating member adapted to cooperate directly with flexible feeding means, and motor operated driving means for said member including parallel shafts, 205 spur gears driven by said shafts respectively, a spur gear meshing with one of said gears, an internal gear driven by said last mentioned spur gear, planet gears meshing with 210 said internal gear and the other of said first mentioned spur gears, and driving connections between said planet gears and said feed operating member.

In testimony whereof I affix my signature.

LOUIS A. MAXSON.
